UNITED STATES PATENT OFFICE.

MICHAEL D. BINGHAM, OF SOMERVILLE, MASSACHUSETTS.

SASH-WEIGHT.

1,077,586.

Specification of Letters Patent.

Patented Nov. 4, 1913.

Application filed January 4, 1912. Serial No. 669,688.

To all whom it may concern:

Be it known that I, MICHAEL D. BINGHAM, a citizen of the United States, and a resident of Somerville, in the county of Middlesex and State of Massachusetts, have invented certain new and useful Improvements in Sash-Weights, of which the following is a specification.

This invention relates to sash weights composed of sections or units adapted to be detachably coupled together to form a complete weight of any desired sash-supporting capacity.

The invention has for its object to provide a simple and effective sash weight unit, adapted to be conveniently and securely coupled to another duplicate unit or units, the connected units being inseparable from each other when the units hang in alinement with each other, and the form of the coupling parts, or members of the units being such that when the units are relatively rough castings in accordance with the usual practice, the coupling members require no grinding or other finishing to adapt them for use.

The invention consists in the improvements which I will now proceed to describe and claim.

Of the accompanying drawings which form a part of this specification,—Figures 1 and 2 represent elevations of different sides of a sash weight composed of two units embodying my invention, one of the units being broken away; Fig. 3, represents a section on line 3—3 of Fig. 2; Fig. 4 represents a section on line 4—4 of Fig. 2; Fig. 5 represents a view similar to Fig. 3 showing the lower unit at an angle to the upper unit preparatory to engagement therewith; Fig. 6 represents in perspective the interlocking ends of two separated units.

The same reference characters indicate the same parts in all the figures.

The sash weight unit of my invention constitutes one of a series of two or more duplicate units, so that a description of one unit will be sufficient. The said unit is composed of an elongated body 12 which is shown as rectangular in cross section and having four flat longitudinal sides or faces, although the body may be of circular or other form in cross section.

In the lower end portion of the body 12 is formed a transverse recess having a back 13 formed by an extension of one of the sides

of the body, and a top 14 formed by the lower end of the main portion of the body 12.

15 represents a narrow elongated horn or seat which projects from the back 13 across the recess and has an upper surface which is substantially at right angles with the longitudinal axis of the body 12, and is preferably curved or inclined downwardly from its longitudinal center to its edges to form an extended bearing for a head 20 on the upper end of a duplicate unit.

16 represents a stop projecting downwardly from the top 14 of the recess and made narrower than the body 12, and also narrower than the depth of the recess, so that the stop is adapted to project between ears 21 which support the head 20, as shown by Fig. 2, and to engage said head to prevent its withdrawal from the recess, as shown by Figs. 1 and 3.

The opposite end portion of the body 12, is provided with upwardly projecting ears 21, the upper portions of which are connected by a head 20, preferably having the form in cross section shown by Figs. 3, 4 and 5, one side of the head being substantially flat, and the opposite side convex. Said ears and head form sides or walls of a transverse opening which receives the seat 15 of a duplicate unit when the two units are operatively connected. The head 20 has a narrow rounded lower edge 20^a which bears on the seat 15 of the duplicate unit, as shown by Figs. 1, 2 and 3. The ears 21 are offset from one side of the body 12, so that when two units are connected, their bodies are in alinement with each other.

The end portions of the bearing edge 20^a are curved or inclined downwardly by fillets 20^b (Fig. 2) formed thereon, said bearing edge being thus adapted to conform closely to the form of the upper surface of the seat 15, so that the head has a narrow elongated bearing on the seat, as indicated at the lower portion of Fig. 2.

The head 20 of the upper unit engages the bight of a sash cord 23, the fillets 20^b maintaining said bight in a central position midway between two opposite sides of the weight body. The bearing edge 20^a is located midway between the other two opposite sides of the weight body.

In assembling two units the lower unit is turned substantially at right angles with the upper unit, as shown by Fig. 5, and its

2
head 20 is placed on the seat 15 of the upper unit. The lower unit is then swung downwardly into alinement with the upper unit, the bearing edge of the head 20 turning on the seat, and its opposite edge being raised, as indicated by the arrow in Fig. 5, until it abuts against the stop 16, this occurring when the two unit bodies are in alinement with each other. The narrowness of the bearing edge 20^a enables it to move freely on the seat 15 even though the contacting surfaces of the bearing edge and seat are left rough as they come from the sand mold in which they are cast, said bearing edge being the only part of the lower unit that is in forcible rubbing contact with the upper unit during the operation of alining the units.

The head 20 of the lower unit simultaneously engages the seat 15 and stop 16 of the upper unit, and is supported by the seat and confined by the stop against removal from the seat while the units are in approximate alinement. The ears 21 are preferably provided with shoulders 25, which bear on complementary shoulders 26 on the recess back 13, the shoulders 26 projecting under the shoulders 25 and aiding the seat 15 in supporting the lower unit. The back 13 of the recess in one unit serves as a stop for the shouldered edge of the ears 21 of the other unit and maintains the head 20 in the central position, shown by Fig. 1.

The features of the ears 21 having outer side faces and front edges in alinement with surface portions of the body 12, and having overhanging rear edges with shoulders 25 which closely fit the rear face 13 and the shoulders 26 of a duplicate unit, and also the presence of the horn 15 and stop 16, all co-operate in holding connected units steadily together with no such looseness as to permit

rattling, and also result in leaving a minimum amount of unoccupied space between the units. Although there is sufficient space 45 to permit of connection or disconnection of the units, yet such unoccupied or unfilled space is very slight, and consequently a connected series of units to give the required counterbalancing weight requires less 50 vertical sliding room in the window casing than when a lesser amount of metal is provided in the connecting portions of the units. In other words, I provide the maximum amount of weight for the total length of 55 each complete unit.

I claim:—

A sash weight unit composed of an elongated body one end of which is formed with ears 21 having rounded tops and undercut 60 rear portions presenting convex shoulders 25, said ears being connected by a head 20 having its lower surface rounded and curved from one ear to the other, the outer side faces and the front edges of the ears being 65 in alinement with the surface portions of the said body, the other end of the body being formed with a transverse recess having a curved rear face 13 and with a horn or seat 15 having a transversely rounded 70 upper surface, the portions of the body at the sides of said horn having concave shoulders 26 to receive the convex shoulders 25 of a duplicate unit, the body being also formed with a stop 16 projecting partially 75 across the transverse recess to enter the space between the ears 21 of a duplicate unit.

In testimony whereof I have affixed my signature, in presence of two witnesses.

MICHAEL D. BINGHAM.
